UNITED STATES PATENT OFFICE.

JASPER SLAYMAKER, OF SUNBURY, PENNSYLVANIA, ASSIGNOR OF TWO-THIRDS TO THE SUNBURY WATER COMPANY, OF SAME PLACE.

STOP-COCK FOR WATER-SERVICE SYSTEMS.

SPECIFICATION forming part of Letters Patent No. 569,304, dated October 18, 1896.

Application filed March 17, 1896. Serial No. 583,637. (No model.)

To all whom it may concern:

Be it known that I, JASPER SLAYMAKER, a citizen of the United States, residing at Sunbury, in the county of Northumberland and State of Pennsylvania, have invented a new and useful Stop-Cock for Water-Service Systems, of which the following is a specification.

My invention relates to an improvement in stop-cocks for water-service systems, adapted for introduction in a service-pipe between the street water-main and the building, approximately at the curb or between the parts of the service-pipe owned, respectively, by the water-supply company and the property-owner, and the object in view is to provide means whereby the location of ice in the service-pipe may be determined, to fix the responsibility thereof upon either the property-owner or the company, and at the same time avoid unearthing the entire length of pipe in order to discover the point at which the stoppage exists.

Further objects and advantages of this invention will appear in the following description and the novel features thereof will be particularly pointed out in the appended claims.

In the drawings, Figure 1 is a side view, partly in section, of a stop-cock provided with improvements embodying my invention arranged in a stop-box of the ordinary construction. Fig. 2 is a detailed sectional view of the stop-cock plug and extension to show the location and construction of the test-valve.

Similar numerals of reference indicate corresponding parts in both figures of the drawings.

I designates a cylindrical stop-box, at the lower end of which is located a stop-cock casing 2, connected at opposite ends with service-pipe sections 3. This casing is provided with an upwardly-tapered plug-seat 4, in which is fitted the tapered or frusto-conical plug 5, held in place by means of a cap 6, threaded upon the lower end of the casing. This plug is provided with the usual transverse opening 7, adapted to be arranged in alignment with the diametrically opposite ports of the casing, and this transverse opening is extended upwardly to form a cavity 8 in communication with an axial bore 9. The plug is provided

above the top of the casing with a cylindrical extension 10 and a wrench-seat 11, said bore 9 extending to the upper extremity of the wrench-seat.

Located at the lower extremity of the bore 9 is a valve-seat 12, in operative relation with which is arranged a test-valve 13, having a stem 14, which extends upwardly through the bore, and is provided at its upper extremity 60 with a stop 15 to prevent displacement and at the same time allow vertical movement of the valve.

In connection with the above-described construction I employ a wrench 16, having a tubular stem or shank 17, which terminates at its upper end in a handle 18 and at its lower end in a jaw 19 to fit the wrench-seat 11, and the bore 20 of said stem or shank is provided at its upper extremity with a lateral port 21.

When it is desired to detect the location of a stoppage in the service-pipe, the wrench, constructed as above described, is lowered and applied to the seat 11, thereby bearing against the upper extremity of the stem 14 of the test-valve 13 and unseating the latter against the tension of a spring 22, which is preferably arranged in the opening 7 to hold said test-valve seated when not exposed to pressure within the casing. If the stoppage occurs at 80 a point between the stop-cock and the building or inside of the stop-cock, the pressure in the main will discharge water through the bore 9 and the stem or shank of the wrench, whereas if the stoppage occurs between the 85 stop-cock and the main or outside of the stop-cock no such discharge of water through the bore of the stem will occur.

It will be understood that the construction as above described may be applied to any 90 ordinary form of stop-cock, and by its use it is obvious that considerable time, labor, and expense usually lost in searching for a stoppage can be avoided.

Various changes in the form, proportion, 95 and the minor details of construction may be resorted to without departing from the spirit or sacrificing any of the advantages of this invention.

Having described my invention, what I claim is—

1. A stop-cock for water-service pipes hav-

ing a plug provided in communication with the interior of the casing with a bore, a normally-closed test-valve for controlling said bore and yieldingly held seated, and a sliding stem connected to the test-valve and exposed for exterior pressure to unseat the valve, whereby the test-valve may be unseated simultaneously with the operation of the plug to indicate the position thereof, substantially as specified.

2. A stop-cock for water-service pipes having a plug provided with a wrench-seat, and a test-valve for controlling a port in communication with the interior of the stop-cock casing, and having a stem exposed contiguous to the wrench-seat for contact by a wrench fitted upon said seat, whereby the test-valve is unseated when a wrench is applied to turn the plug, substantially as specified.

3. A stop-cock having a plug provided with an exterior wrench-seat and also provided with an axial bore communicating with the interior of the casing, a test-valve to control said bore, and a stem connected to the test-valve, extending through the bore and ex-

posed contiguous to the wrench-seat for contact by a wrench fitted upon the seat, substantially as specified.

4. A stop-cock for water-service pipes having a plug provided with a wrench-seat and an axial bore communicating with the interior of the stop-cock casing and terminating contiguous to said wrench-seat, a test-valve for controlling the bore in the plug and provided with a stem terminating contiguous to the wrench-seat, and a wrench adapted to be fitted upon said wrench-seat to engage the valve-stem and unseat the test-valve and provided with a bore to communicate with said bore in the plug and terminating at its upper end in an outlet-port, substantially as specified.

In testimony that I claim the foregoing as my own I have hereto affixed my signature in the presence of two witnesses.

JASPER SLAYMAKER.
